UNITED STATES PATENT OFFICE.

CHARLÉ C. WILLIAMS, OF CLEVELAND, OHIO, ASSIGNOR, BY DIRECT AND MESNE ASSIGNMENTS, OF ONE-HALF TO GEORGE E. HARBAUGH AND ONE-HALF TO WEBSTER F. TRAVES, OF CLEVELAND, OHIO.

SPEED-CHANGING MECHANISM.

No. 823,487.

Specification of Letters Patent.

Patented June 12, 1906.

Application filed January 16, 1904. Serial No. 189,323.

To all whom it may concern:

Be it known that I, CHARLÉ C. WILLIAMS, a citizen of the United States, and a resident of Cleveland, county of Cuyahoga, and State of Ohio, have invented a new and useful Improvement in Speed-Changing Mechanisms, of which the following is a specification, the principle of the invention being herein explained and the best mode in which I have contemplated applying that principle so as to distinguish it from other inventions.

My invention relates to means for reducing the speed of a revolving element concurrently with an increase of torque exerted thereby.

Said invention has for its object the consummation of such described result in an efficient and economical manner; and it consists of means hereinafter fully described, and particularly set forth in the claim.

The annexed drawings and the following description set forth in detail certain mechanism embodying the invention, such disclosed means constituting but one of various mechanical forms in which the principle of the invention may be used.

In said annexed drawings, Figure 1 represents a device embodying my invention with the outer cover-plate removed and showing the remaining part partly in transverse section. Fig. 2 represents an elevational view of a part of such cover-plate. Fig. 3 represents an axial section of such device, parts cut by the plane of section being shown in elevation. Fig. 4 represents a detail section taken upon the plane indicated by line 4-4 in Fig. 3.

The mechanism consists of four general parts--viz., the main or body portion A, the cover-plate B, the driving-shaft C, and the driven shaft D--and coöperating with such general parts are certain valves and pistons hereinafter fully described.

The main or body portion A consists of a cylindrical cup-shaped structure, which is provided upon its interior with two pairs of cylinders a a and a' a' , Figs. 1 and 3, open at their inner ends. As shown in Fig. 3, the cylinders a a have their axes located in the same straight line intersecting the axis of the structure, and the axes of cylinders a' a' bear a similar relation to one another, the intersecting line, however, lying in a separate plane perpendicular to the structure's axis.

These cylinders are located from each other an angular distance of ninety degrees. Each pair of cylinders has operating, respectively, therein two pistons a^2 a^2 and a^3 a^4 , each pair being connected by a scotch yoke a^4 and a^5 , respectively, the guide-surfaces of such yokes being located at right angles relatively to each other, as shown in Fig. 1. These guiding-surfaces form guides for a common cross-head a^6 , whose center is formed with a bearing for the wrist-pin d of a crank d' , formed on the crank or driven shaft D. The axis of said shaft is coincident with the axis of the structure. It will therefore be seen that should the main or body portion A be rotated while the shaft D is stationary the pistons would be simultaneously reciprocated in their respective cylinders, said pistons occupying the same position in their respective strokes relatively to the cylinders in succession--that is, the pistons will successively reach the outer or the inner ends of their respective strokes.

Establishing communication between the interior of each cylinder and the interior of member A is a port a^7 , passage through which is controlled by a plunger-valve a^8 , seated in a suitable chamber a^9 , said valve being capable of varying the port-opening from zero to the maximum or complete opening. Each such valve is provided with a stem a^{10} , which passes through the side of said member, a suitable gland a^{11} and packing being provided, as shown.

The cover-plate B is bolted over the opening of member A, the adjacent ends of the valve-stems passing through such plate, suitable glands b and packing being provided to render the joints so formed water-tight. The entrance of shaft D through member A is also provided with a suitable gland d^2 and packing therefor. The entire outer structure above described hence forms a watertight interior chamber or reservoir E, inclosing the crank d' and pistons connected thereto. The plate B has formed in its central portion an opening b' of rectangular cross-section, in which is fitted the end of the driving-shaft C. The ends of the valve-stems are all connected to a common spider F, which is arranged to slide upon a bearing a^{12} , formed upon a central hub a^{13} , integral with the part A. The valve-stem ends are thread-

ed into the ends of their respective spider-arms, are slotted to allow them to be turned by a screw-driver, and provided with a lock-nut a^{14} for fixing their positions relatively to the said spider. Such construction allows the valves to be adjusted in their chambers, as will readily be understood. The spider is provided with a hub f , provided with a circumferential groove f' , which may be engaged during rotation by suitable manually-operated means (not shown) and so be caused to simultaneously move the valves to open their respective ports. The entire interior of the chamber E and cylinders $a a'$ is filled with a light lubricating-oil.

The device operates as follows: Let it be assumed that the driving-shaft C is being driven and the valves are set, so as to provide a full opening of the cylinder-ports, and hence a free passage of oil into and out of the cylinders, and that such ports are of a cross-sectional area such that the operation of the pistons in their respective cylinders will exert only a small amount of pressure upon the pistons' heads. Such being the case, the rotation of the driving-shaft C would allow of such piston operation and a concurrent state of rest on the part of the shaft D . It will be understood that such operation involves a state of rest on the part of the pistons relatively to the earth; but these pistons are, however, on account of the eccentricity of the location of the cross-head placed in a state of reciprocation relatively to their respective cylinders, during which oil is pumped into and out of the cylinders from and into the chamber E , and so alternately displaced therefrom and replaced. Now let it be assumed that the valves are moved to restrict the port-openings. In such case there will immediately result a state of pressure in the cylinders and upon the pistons. Since all of the cylinders are in communication with the interior of the chamber, such pressure is communicated throughout the latter equally in all directions. The piston-surface against which the pressure is exerted inwardly toward the axis of the device—that is, the piston area within the cylinders—being greater in area than the piston-surface receiving a pressure in the opposite direction, the ultimate result will be a retarding of the relative

motion of the cylinders and pistons. The amount of such retardation will of course be directly proportionate to the pressure, and the intensity of the pressure will be inversely proportionate to the area of the port-openings. A diminution of such motion hence means an actual movement of the crank-shaft. Such movement hence takes place and the crank-shaft is caused to revolve under such conditions in the same direction as does the driving-shaft and at a speed dependent upon the port area and load upon such crank-shaft. Assuming that the load remains the same, it will be seen that the said shaft D may be rotated at speeds varying from zero to that of the driving-shaft. When the latter speed is attained, it will be seen that the ports must be completely closed, or substantially so. In such latter case it will be seen that the two rotary parts are locked to one another, since no expulsion or suction of oil, and hence no relative movement of the pistons and their respective cylinders, is allowed to take place. The mechanism therefore acts as a clutch when the valves are moved to completely close the ports.

Having described my invention in detail, that which I particularly point out and distinctly claim is—

In speed-changing mechanism, the combination of two rotatable members; a liquid-reservoir connected with one of said members; two pairs of pump-cylinders carried in said reservoir and having fluid connection therewith; two pairs of pistons adapted to reciprocate within said pump-cylinders, respectively; yokes connecting said pairs of pistons, respectively, and provided with guiding-surfaces; a crank-shaft connected to the second rotatable member; a cross-head journaled on said crank-shaft and guided on the surfaces of said yokes; and manually-operated means adapted to control the amount of liquid flow between said reservoir and said pump-cylinders.

Signed by me this 9th day of January, 1904.

CHARLÉ C. WILLIAMS.
